STEAM GENERATING SYSTEM

Alick Clarkson, Elmhurst, Ill.

Application September 8, 1936, Serial No. 99,736

7 Claims. (Cl. 122—250)

This invention relates to a steam generating apparatus, usually of the automatic or semi-automatic type. This apparatus is of high efficiency in relation to its evaporative capacity, and 5 is small in size, light in weight, easily controlled and capable of being manufactured from ordinary commercial boiler material.

The invention contemplates a generating apparatus in which the water is evaporated while 10 passing through a coil or coils and one of the objects of the invention is to so construct the apparatus that the hot gases are forced to pass through the apparatus in such manner as to heat the coils most efficiently with a minimum 15 destructive effect upon the casing or other parts of the furnace.

The principal object of the invention is to provide an improved arrangement of the boiler coils, together with improved spacing and supporting 20 means for these coils so as to retain the coils substantially in the desired position while permitting certain necessary expansive and contractive movements.

Another object is to provide a generator construction which permits a maximum absorption 25 of both radiant and conduction heat in the water passing through the coil or coils.

A further object is to provide a steam generator having a generating coil or coils so constructed that the coil or coils may be considerably overheated without damage.

The generator according to the invention comprises a bank of connected pipe coils positioned one within another about a common central axis 35 and the innermost coil enclosing a central heating space, the turns of adjacent coils being offset so that the turns of one coil are staggered with respect to the turns of adjacent coils, in which a plurality of separate spacers are positioned at intervals between adjacent turns of the coils, certain of the spacers being attached to both of the pair of turns and other spacers being attached to only one of the turns.

One form of the invention is illustrated in the 45 accompanying drawings in which:

Fig. 1 is a central vertical sectional view of the generator;

Fig. 2 is a detail plan view of the outer generating coil;

Fig. 3 is a cross-sectional view on line 3—3 of Fig. 2;

Fig. 4 is a detail plan view of the inner generating coil;

Fig. 5 is a vertical section on line 5—5 of Fig. 55 4; and

Figs. 6 and 7 are detail vertical sections taken on the lines 6—6 and 7—7 respectively, of Fig. 4.

Referring first to Fig. 1, A designates the steam generator provided with burner B, the steam generator preferably comprises a casing 10 carried on supports 11 and provided with a flue 12, an air duct 13, and a flame ring 14, through which is passed the products of combustion from the burner B, or heating gases from some other type of combustion device.

The burner B, assuming that oil is to be used as a fuel, preferably comprises an oil atomizer 30 projecting through a boss 31 on the top of the air duct 13. At 32 is shown an ignition device for igniting the oil spray from the atomizer. 15 The oil is admitted to the atomizer through a port controlled by a diaphragm valve which opens only when a certain minimum fluid pressure is supplied. At lower pressures the valve automatically closes. Arranged below the atomizer is a cylindrical structure or fire-pot 33 having an inturned curved lip 34 at its upper end. The structure 33 provides a combustion chamber and is spaced at its lower edge from the flame ring 14 with the interposition of an annulus 35 arranged to provide an air port 36 between it and the combustion chamber and an air port 37 between it and the flame ring. Above the combustion chamber is a cone 38 formed with air openings 39. Another ring 40 is arranged above 20 the upper edge of cone 38 and is preferably provided with an inturned flange 41. This specific form of burner is merely shown by way of example and it may be briefly stated that the air supply from duct 13 flows in between the several members in such manner as to provide a stabilized ignition zone within the rings 38 and 40, and air currents are set up within fire-pot 33 so as to provide a substantially complete combustion, the hot products of combustion being 25 discharged through flame ring 14 into the central heating chamber surrounded by the pipe coils.

The specific form of burner hereinabove described by way of example is disclosed and claimed in a division of the present application, said divisional case being filed under date of June 21, 1937, Serial No. 149,466. It will be understood that other types of burner devices could be used with the improved steam generating apparatus herein disclosed and claimed.

Preferably soot removers 42 are arranged between the inner and outer coils and are connected with a circular pipe 43 which receives steam, the soot removers consisting of tubular 50 55

members perforated for ejection of steam between the turns of the generating coils. Steam is introduced into the circular pipe 43 at intervals or if and when the pipe coils become sufficiently sooted to require it.

The steam is generated in a bank of connected coils positioned symmetrically about a central vertical axis, the inner coils 15 and 16 being preferably of larger pipe diameter than the outer coils 17, 18, 19 and 20. This bank of coils, which for convenience will be designated as a whole by the letter K, is arranged between a body of refractory material 21 at the end of the generator opposite burner B, the lower end as the apparatus is shown, and a body of refractory material 22 at the upper end of the structure which is arranged against a baffle plate 23 having a flared lip 23'. Metal seating members 24 and 25 are preferably arranged respectively between the lower body of refractory material and the bank of coils, and between the bank of coils at the top and the refractory body 22 and lip 23'.

The axial lengths of the coils diminish from the inner coil to the outer coil, giving the bank of coils a double frusto-conical configuration. The space in the generator in which the bank of coils K is located, that is, the space between the lower refractory material 21 and the upper refractory material 22 is of similar configuration so that a 30 tapered passageway is provided for the furnace gases as they move from the inner coil to the outer coil and to the space 26 outside of the bank of coils, which space communicates with flue 12. As the gases cool and contract, they are brought into closer contact with the coils which increases the efficiency of the apparatus, this efficiency being further increased by having the outer coils of smaller pipe diameter than the inner coils.

The feed water is forced into the pipe coils through nipple 27 at the outer end of coil 20, and the steam and water mixture is discharged from the inner pipe coil 15 through a suitable connection not here shown.

Returning now to that portion of the generator which forms the particular subject matter of this invention, the inner and outer sets of coils are of similar construction, except for the difference in the number of coils or helices and the difference in pipe size. The coils are not true helices but each consists of a plurality of circular loops or turns, each turn being substantially horizontal throughout nearly 360° and connected with the next higher or lower turn by offsets 44. Outer coils 18 and 19 are connected at one end of the bank of coils by the offset 44c (see Fig. 2). Coils 19 and 20 and also coils 17 and 18 are connected at the opposite end of the bank of coils by similar offsets. Inner coils 15 and 16 are connected in a similar manner at one end of the bank. Coils 16 and 17 are joined by an outside connection. These end connections are so inclined that the turns of one coil are staggered with relation to the turns of an adjacent coil of the bank. That is, the loops or turns of coil 16 are positioned opposite the spaces between the turns of coil 15, and so on. This staggered relationship of the loops or turns of the several coils exists throughout substantially the entire 360° lengths of the turns. Therefore the hot gases are forced to follow a sinuous path between the staggered coils and the gases are forced into intimate contact with a maximum of the pipe surfaces thus effecting a maximum heat exchange between the gases and the fluids in the coils.

The coils are separated and supported by sinuous

spacers 45 to which, however, the coils are not attached. There may be any suitable number of these spacers. The sinuous spacers are flexible, and they allow expansion and contraction of the coils while giving the coils the necessary support one on the other.

There are also a plurality of separate spacers 46 and 51 positioned at suitable intervals between adjacent or successive turns of the coils, certain of these spacers being attached to both of the pair of turns between which the spacer is interposed, and other spacers being attached to only one of these turns. In the example here shown, the spacers 46 (Fig. 6) are arranged between the coils at substantially diametrically opposed positions. These spacers 46 are welded or otherwise firmly secured to the turns 47, 48 and 49, 50 between which they are disposed. The turns are thus rigidly tied together at these points.

The spacers 51 (Fig. 7) are arranged between the turns at substantially diametrically opposed positions and at 90° from the spacers 46. One of these spacers 51 is welded to one of the turns between which it is interposed, for example, pipe 47, but is not attached to the other pipe 48 of the pair. Similarly, a second spacer is welded to pipe 49 but not to the other adjacent pipe 50.

Each of the spacers 46 and 51 is provided with a laterally extending finger portion which engages the pipe turn of a laterally adjacent coil. For example, the spacer 46 between turns 47 and 48 (Fig. 6) has a finger 46' engaging the turn 49 positioned opposite the space between turns 47 and 48.

It will be noted that the sinuous spacers 45 are used at suitable circumferential intervals between the respective sets of spacers 46 and 51. The combination of the three sets of spacers 45, 46 and 51 gives adequate support to the elements 40 of the bank of coils K in which the steam is generated, as against distortion of permanent character, while permitting the movements of the coil elements (especially rotary movement around the central axis) under temperature changes.

I claim:

1. In combination with a substantially helical steam generating pipe coil, a plurality of spacers between the turns of the coil which are attached to both turns, and a plurality of spacers between said turns which are attached to one turn only.

2. In combination with a substantially helical steam generating pipe coil, pairs of diametrically arranged spacers between the turns of the coil which are attached to both turns, and a plurality of diametrically arranged spacers at 90° from the first mentioned spacers which are attached to one turn only of the turns which they space.

3. In combination with a substantially helical steam generating pipe coil, pairs of diametrically arranged spacers between the turns of the coil which are attached to both turns, and a plurality of diametrically arranged spacers at 90° from the first mentioned spacers which are attached to one turn only of the turns which they space; and means for supporting the turns against movement in the direction of the axis of the coil while permitting circular movement of the coil.

4. A steam generator comprising a plurality of pipe coils centered about a common central axis, the turns of which are offset so that the turns of one coil are staggered with respect to the turns of adjacent coils, substantially diametrically arranged spacers positioned between each pair of adjacent turns of a coil and attached

to both turns, and substantially diametrically arranged spacers positioned between these turns and arranged 90° from the first-mentioned spacers and attached to one of the turns but unattached to the other.

5. A steam generator comprising a plurality of pipe coils centered about a common central axis, the turns of which are offset so that the turns of one coil are staggered with respect to the turns of adjacent coils, substantially diametrically arranged spacers positioned between each pair of adjacent turns of a coil and attached to both turns, and substantially diametrically arranged spacers positioned between these turns and arranged 90° from the first-mentioned spacers and attached to one of the turns but unattached to the other, each of said spacers having a laterally projecting finger engaging the turn of an adjacent coil positioned opposite the space between the pair of turns, the first mentioned pair of turns.

10. A steam generator comprising a plurality of pipe coils centered about a common central axis, the turns of which are offset so that the turns of one coil are staggered with respect to the turns of adjacent coils, and a plurality of separate spacing blocks positioned at intervals between adjacent turns of a coil, each block between a pair of turns having a laterally projecting finger engaging the turn of an adjacent coil positioned opposite the space between the pair of turns, each spacing block being attached to one of the pair of turns.

15. A steam generator comprising a plurality of pipe coils centered about a common central axis, the turns of which are offset so that the turns of one coil are staggered with respect to the turns of adjacent coils, and a plurality of separate spacing blocks positioned at intervals between adjacent turns of a coil, each block between a pair of turns having a laterally projecting finger engaging the turn of an adjacent coil positioned opposite the space between the pair of turns, each spacing block being attached to one of the pair of turns.

20. A steam generator comprising a plurality of pipe coils centered about a common central axis, the turns of which are offset so that the turns of one coil are staggered with respect to the turns of adjacent coils, and a plurality of separate spacing blocks positioned at intervals between adjacent turns of a coil, each block between a pair of turns having a laterally projecting finger engaging the turn of an adjacent coil positioned opposite the space between the pair of turns, certain of the blocks being attached to both of the pair of turns, and other blocks being attached to only one of these turns.

ALICK CLARKSON.
